(57) **CLAIM**

The ornamental design for a bicycle display device, as shown and described.

DESCRIPTION

FIG. 1 is a front perspective view of a bicycle display device having five display components adjustably attached to a mounting assembly (a pair of lateral bar, a pair of ball joints and a pair of mounting brackets) in accordance with our new design;

FIG. 2 is a front elevational view of the bicycle display device illustrated in FIG. 1;

FIG. 3 is a rear elevational view of the bicycle display device illustrated in FIGS. 1 and 2;

FIG. 4 is a left side elevational view of the bicycle display device illustrated in FIGS. 1-3;

FIG. 5 is a right side elevational view of the bicycle display device illustrated in FIGS. 1-4;

FIG. 6 is a top plan view of the bicycle display device illustrated in FIGS. 1-5; and,

FIG. 7 is a bottom plan view of the bicycle device illustrated in FIGS. 1-6.

The broken line showing of environment in FIGS. 1 and 2 is for illustrative purposes only and forms no part of the claimed design.
